cago, Ill., a corporation of DelawareApplication August 25, 1932, Serial No. 630,399,
and in Great Britain August 25, 1931

14 Claims. (Cl. 178—51)

The present invention relates to alternating current telegraph systems and is more particularly concerned with systems of the type in which the so-called carrier alternating current is of a frequency which is high compared with the frequency of interruption constituting the signals. It may readily be proved that when the flow of current of carrier frequency is started or stopped, currents are generated having a frequency range which is theoretically infinite. If the circuit in question is arranged for single channel working only so that all these currents can be transmitted, no difficulties are encountered and the signals arrive at the receiving end without sensible distortion. If, however, as will usually be the case, the circuit is arranged for multi-channel working with carrier currents of different frequencies, it is important that the currents generated when current of any particular carrier frequency is started or stopped shall be confined to a given frequency range so as not to interfere with signals sent on other carrier frequencies.

The ideal to be aimed at in working systems of this type is that the envelope of the signal currents shall be rectangular and this will ordinarily only be attained if an infinite frequency range is possible. Where, as for commercial multi-channel working, only a limited width of side band is available, for instance 60 cycles on each side of the carrier frequency, distortion is introduced and the envelope assumes a more nearly sinusoidal shape. This has the undesirable effect of making the signals more difficult to receive satisfactorily so that for the same factor of safety the speed of transmission is reduced. The chief object of the invention is to provide an arrangement whereby in a system of the type described this distortion is counteracted and the signals are restored to something approaching their original rectangular form and are independent of the magnitude of the incoming signal voltage over wide limits and moreover are independent of the presence of signals transmitted over adjacent frequency channels. This result is achieved by the use of apparatus of a very simple and inexpensive character.

It will be appreciated from what has been said above that for the operation of a multi-channel system some kind of filter or tuning arrangement is essential even if the carrier frequency as originally generated is kept accurately to its nominal value. Consideration will show also that the tuning device is preferably not such as to be sharply resonant but to give a response which is substantially the same for the whole width of side

band concerned. In other words response plotted against frequency should give a curve in the general form of a truncated cone with a substantially flat top. In arrangements previously used a band pass filter closed with its characteristic impedance has generally been employed for restricting the response of the equipment to the particular frequencies concerned, and giving very large attenuation to signals of frequencies outside this frequency band, but this is always an expensive piece of equipment and according to the invention satisfactory results are obtained by the use of simple tuned circuits arranged to have a uniform response over the band required, but in which the attenuation may not rise to such a high value for frequencies considerably outside this band as in the case of an ordinary band pass filter. It is arranged that the tuning circuit has two slightly different resonant frequencies which are preferably equidistant from the carrier frequency, so that the response curve of such an arrangement will have two humps symmetrically located with respect to the carrier frequency which will correspond to the depression between. This tuning arrangement is employed at both the transmitting and receiving ends of the circuit but the frequencies to which the filtering arrangements are tuned at the receiving end are closer together so that the two humps in the response curve overlap with the result that the combination of the two tuning circuits produces a peak which is substantially flat over the whole width of the side bands concerned.

According to one feature of the invention, in an alternating current signaling system employing a carrier current of a particular frequency the input from the line is passed through a simple resonant circuit or circuits responsive to the carrier frequency, is limited by means of a gas discharge tube and is then fed by way of a resistance and a further tuned circuit and a rectifier to a thermionic valve having a responding relay in the anode circuit.

According to another feature of the invention, signals transmitted with one carrier frequency produce corresponding reductions in the cathode-anode impedance of a thermionic valve this circuit including an alternating current source of another carrier frequency and a transformer tuned by means of a condenser to this frequency so that when the impedance of the valve is reduced in response to a signal an alternating voltage of the second frequency will be impressed on the secondary of the transformer which is connected to a further signaling line.

A further feature of the invention is that at the receiving end the input is fed to the grid of a thermionic valve by way of a resistance-condenser combination the values of which are so chosen that owing to the changes in the potential of the grid due to the charging of the condenser from rectified alternating current signals derived from the anode circuit of the valve, incoming signals of large amplitude cause a large change in the grid potential which persists so as to reduce the effect or entirely prevent the passage of signals of small amplitude occurring between the large amplitude signals.

Still another feature of the invention is that in an alternating current signaling system arranged for signaling by means of a plurality of carrier frequencies, the interrupted carrier currents are passed at the transmitting end through resonant circuits tuned to two frequencies respectively slightly above and slightly below the carrier frequency while the received currents are passed through resonant circuits tuned to two different frequencies also respectively slightly above and slightly below the carrier frequency so that the response curve of the transmitting and receiving filters in tandem is substantially flat over the range representing the width of the sidebands employed.

The invention will be better understood from the following description of one method of carrying it into effect which should be taken in conjunction with the accompanying drawings comprising Figs. 1, 2 and 3. Of these, Fig. 1 shows the complete circuits of one channel of a multi-channel carrier telegraph system suitable for the operation of teleprinters, Fig. 2 shows an arrangement for readily converting signals of one carrier frequency into signals of a different carrier frequency and Fig. 3 shows typical response curves for the transmitting and receiving filter circuits and the combined response curve for the two circuits in tandem.

Referring first to Fig. 3, the curve A represents the response curve of the tuning circuit at the transmitting end and it will be seen that it gives two maxima corresponding to resonant frequencies c_1 and c_2 equidistant from the carrier frequency F in respect of which the response is appreciably less. The curve B representing the response of the tuning circuit at the receiving end is of similar form but the humps at the resonant frequencies c_1 and c_2 are so close together as to overlap so that there is now no depression at the carrier frequency. The curve C shows the combined effect of the transmitting and receiving filtering circuits and it will be seen that a substantially flat top is obtained within the limits of the effective side bands which are assumed to be frequencies c_1 and c_2 . It may be mentioned that it is not satisfactory for multi-channel operation to obtain this curve by combining transmitting end and receiving end curves which are not symmetrical about the carrier frequency as the discrimination between channels cannot be so large as with the arrangement described. It may be mentioned also that it is preferred to obtain the more pointed curve at the receiving end though this is not essential.

Referring now to Fig. 1, 1 represents a generator serving for the continuous generation of alternating currents of the carrier frequency which are fed by way of the signaling device 2 represented as a simple key and the variable resistance 44 to the fixed resistance 3. Connected across this resistance is a resonant circuit

comprising the condenser 4, resistance 5 and inductance 6 which is tuned to a frequency say slightly below the carrier frequency. A small portion of inductance 6 is included in the second resonant circuit comprising inductance 7, condenser 8 and low resistance 9, this circuit being tuned to a frequency as much above the carrier frequency as that of the first circuit was below it. The resistance 9 is connected across the common input leads 10 and 11 which are connected by way of similar tuning circuits to the transmitters corresponding to the other carrier frequencies. The common input passes to an amplifier 12 of any suitable type and thence to the signaling lines 13 and 14. It will be understood that these series tuned circuits can be replaced by parallel tuned circuits and resistances to give filters having similar characteristics.

At the incoming end of the line is a common input transformer 15 from the secondary of which the signals are fed to the various receivers for the different carrier frequencies. The receiving equipment for each frequency includes two circuits tuned as at the transmitting end to slightly different frequencies on either side of the carrier frequency but these frequencies are not the same as those to which the filtering equipment at the transmitting end is tuned. The arrangement of the tuning circuits, however, is similar, the first circuit comprising resistance 16, inductance 17 and condenser 18, while tapped across a small portion of inductance 17 is a second circuit comprising inductance 19, condenser 20 and low resistance 21 across which is connected the primary of the transformer 22. One end of the secondary of transformer 22 is connected to the grid of the thermionic valve 23 and the other end is connected to the cathode by way of resistance 24 shunted by condenser 25 and resistance 27 shunted by condenser 26. For reasons which will appear subsequently, resistance 24 is large compared with resistance 27, while condenser 26 is of considerably greater value than condenser 25. Grid potential is controlled from the anode circuit by incoming signals by means of the drop in resistance 30 in the cathode-anode circuit in conjunction with rectifier 28 and in addition a permanent bias is provided by the potentiometer 29. The anode circuit of the valve 23 includes the transformer 31 which is provided with three windings across one of which is connected the neon tube 32. The purpose of this arrangement is to limit the amplitude of the received signal in the manner described in my application Serial No. 599,221, filed March 16, 1932. By means of the other winding of the transformer 31 signal currents are passed by way of resistance 45 to the tuned circuit consisting of the condenser 33 and the primary of the transformer 34, the tuning in this case being to the carrier frequency. The secondary of the transformer 34 is connected to the grid of the valve 40 by way of the rectifier 35 and resistance 38. Negative grid bias is applied by means of the battery 48 and the use of condenser 37 which is shunted by the resistance 36 ensures in conjunction with rectifier 35 the application of a steady potential to the grid when a signal is received. The responding relay 41 is connected in the anode circuit of the valve 40 in series with the usual anode battery 42 which may have a voltage of 130. The responding relay is provided with a bias winding connected to the anode battery in series with resistance 49 and this ensures that the operation of the relay is unlikely to be upset by changes in the voltage of

the battery. The contacts of the relay are shown connected to give double current working in the output circuit over leads 46 and 47 but obviously any suitable connections may be made.

- 5 The valves used are of the indirectly heated type and the heaters are shown connected in series to be supplied from battery 48 which may have a voltage of 24. A resistance 43 may be used to bring the current to the desired value or the
 10 heaters of corresponding valves in the receiving equipment for other channels may be included in the series circuit. Alternatively provision can be made if desired for supplying the heaters from an alternating current source of supply without
 15 otherwise altering the operation of the signal receiver.

Considering now the operation of the circuit, when the key 2 corresponding to the channel shown is closed, currents of the appropriate carrier frequency are passed to the tuned circuits at the transmitting end and are amplified by the amplifier 12 and transmitted over the line. In a similar manner currents of the other carrier frequencies concerned may be flowing over the line from their respective transmitters. Furthermore, as previously pointed out, when the carrier currents are started or interrupted, currents of a large number of unwanted frequencies are generated which are not completely suppressed by
 25 the somewhat coarse filtering circuits used.

At the receiving end the filtering arrangements though of a simple nature are nevertheless sufficiently selective to ensure that the signals passed to the receiving equipment for any one channel shall contain a very large proportion of signals of the correct frequency and consequently the power of the correct frequency signals represents practically the whole of the total power. As previously mentioned the grid potential of
 35 the amplifying valve 23 is controlled from the anode circuit by the drop in resistance 30. The use of the condenser-resistance combination 26 and 27 in conjunction with the rectifier 28 ensures that alternating current signals in the anode circuit will charge up the condenser 26 and thus increase the negative grid bias. The potentiometer 29 enables a positive potential to be obtained to counteract the large grid voltage which would otherwise be produced when no
 45 signal was present. The values of condenser 26 and resistance 27 are so chosen that the discharge time of the condenser is longer than the interval between successive signal pulses and consequently when a current of large voltage
 55 amplitude is received, a considerable negative grid bias is generated which persists during the time that a small voltage is applied corresponding to the interval between successive signal pulses. The effect of this arrangement is that due to the grid bias the small signal is not amplified to any extent and thus the separation between successive signal pulses is accentuated. This serves to compensate for the effect of the limiting arrangement in the succeeding stage the
 65 tendency of which particularly in the case of large signals having a substantially sinusoidal envelope, is to increase the signal period and reduce the spacing interval. The resistance 24 which is not essential for the satisfactory work of the circuit is included to prevent the flow of grid current which will take place on receipt of a large signal from producing any appreciable effect on the state of charge of condenser 26. The desirability of this is that since grid current is
 70 very small in amount compared with anode cur-

rent any change of potential which might be produced by the flow would be effected slowly relatively to the signal pulses and thus the conditions of operation would be rendered different according as a short or long signal had been received.

In order to produce this result satisfactorily resistance 24 must be of a high value compared with resistance 27 and 5 megohms has been found suitable in practice. In order, however, to avoid prejudicing the amplifying properties of the valve by the introduction of a high impedance into the grid circuit, condenser 25 is shunted across resistance 24 to provide a low impedance path for the alternating currents. It will be appreciated, however, that the resistance-condenser combination 24 and 25 is not required to increase the time during which the negative grid potential due to received signals persists, and consequently the discharge time of the combination 24 and 25 must be sufficiently short that it can follow the signal envelope. For this purpose it is suitable for the condenser 25 to have a value of .001 mf. if resistance 25 is 5 megohms as suggested and the maximum signal impulse frequency is about 30 cycles per second. In these
 80 circumstances condenser 26 should have a value of at least 4 mf. and resistance 27 which is small compared with resistance 24 may be $\frac{1}{2}$ megohm. As regards the value of resistance 30, it is necessary that the power in this resistance shall be
 85 sufficient to maintain the charge on condenser 26 even when the charging potential is applied intermittently for very short periods as would occur when impulse signals of the maximum impulse frequency are received, in which case the
 90 signal envelope attains a maximum value for only a very short period during each impulse.

The value of resistance 45 determines the amplitude of the signal voltages received across the windings of transformer 34. If the value of
 95 resistance 45 is increased, the frequency band within which the voltage across transformer 34 is sufficient to cause anode current to flow in valve 40 is reduced and thus this resistance can be used to control the width of the frequency band within which the signals must lie in order to cause the operation of relay 41. As the beginning and end of a signal impulse consist of side band frequencies removed from the carrier frequency, it follows that alteration of resistance
 100 45 may be used to vary the time during which relay 41 remains operated in response to an impulse signal of given length.

It is an important feature of the receiving circuit that the normal negative grid-cathode bias
 110 of the rectifying valve 40 is very considerably greater than that required to prevent anode current from flowing. Hence no anode current is produced until a voltage above a predetermined value is applied to the grid of the valve 40 and thereafter a small percentage increase in this voltage will produce full anode current from the valve. Thus, since the anode current is critically dependent on the applied voltage to the grid, it is important that the incoming signal
 115 voltage to this part of the receiving system shall be controlled to be constant within very narrow limits in spite of variations in the initial signal voltage. This control it will be appreciated is obtained by means of the gas discharge tube 32, 120 preferably a neon lamp, which acts to limit the received signal to a constant amplitude. The voltage applied to the grid is then determined entirely by the frequency of the signal in relation to the frequency-impedance characteristics
 125 130
 135 140
 145 150

of the tuned circuit to which it is applied. More specifically, if a signal consists almost entirely of the carrier frequency, the tuned circuit 33, 34 will be in resonance and will have its maximum 5 impedance and consequently the voltage passed to the secondary of transformer 34 will be a maximum. As the signal departs from the resonant frequency, the impedance of the tuned circuit will decrease and consequently more of the 10 applied voltage will be absorbed by resistance 45 so that a point is soon reached at which the applied voltage is insufficient to cause a flow of anode current sufficient to operate relay 41.

It will be appreciated that for the limiting 15 action of the neon lamp to produce the desired effect it is important to employ some filtering arrangement in the preceding stage to ensure that the voltage of signals of the required frequency is always practically equal to the total 20 voltage of the limited signals so that its magnitude is independent of the presence of currents of other frequencies. This permits the use of a simple filter or tuned circuit in the succeeding stage to prevent currents of other frequencies 25 from causing operation of the responding relay.

As regards the resistance-condenser combination 36 and 37, this operates in conjunction with the rectifier 35 to produce a steady voltage on the grid and thus give rise to a substantial 30 steady current in the anode circuit. It is clear that the condenser must not retain its charge between signal pulses while at the same time it should not lose it appreciably between individual pulses of carrier frequency constituting a signal 35 pulse. The values of the condenser and resistance must be chosen with this in mind and also the desideratum that the signal distortion occurring due to the time taken to charge the condenser should be compensated by the time 40 taken to discharge the condenser through resistance 36. The resistance 38 is employed so that the potential of the condenser 37 may rise to a value somewhat higher than would ordinarily be the case if the limit set by the flow of 45 grid current were applicable. Accordingly condenser 37 may discharge appreciably between carrier frequency pulses without the voltage across its terminals dropping to the value to which it would have been limited by the flow of 50 grid current in the absence of resistance 38.

It should be mentioned that the tap of inductance 6 which is included in the second resonant circuit should be small so as not to disturb the properties of the first resonant circuit, and 55 for a similar reason it is important that the resistance 9 should be of comparatively small value. It will be appreciated that the same reasoning applies to the tap of the inductance 17 and the resistance 21 located at the receiving end, 60 these circuits being of the same design as those at the transmitting end.

It may happen in certain circumstances that it is desirable to convert signals of one carrier 65 frequency into signals of a different carrier frequency; such a necessity might arise for instance in case multi-channel working took place over an important trunk to a distributing point and the signals were then transmitted to the various receiving points by means of single channel working. This conversion can readily be 70 effected without the use of any moving parts by a slight modification of the arrangement shown in Fig. 1 which is illustrated in Fig. 2. The complete circuit at the receiving station has 75 not been shown but it is assumed that the valve

50 occupies the same position as the valve 40 in Fig. 1. Instead of the responding relay the anode circuit of the valve 50 includes the secondary of a transformer 51 fed from the source 52 which supplies alternating current of the carrier frequency to which it is desired to convert. The circuit also includes the primary of a transformer 53 which in conjunction with the condenser 54 is tuned to have a high impedance to currents of other frequencies including the original carrier frequency. When signals of the original frequency are received causing the anode current of the valve 50 to increase, the anode-cathode impedance of the valve decreases from practically an infinite value to a comparatively low value and accordingly an alternating voltage of the required carrier frequency is obtained across the secondary winding of the transformer 53 and thus is fed to the outgoing line 55. Consequently each time currents of the original carrier frequency are received corresponding currents of the new carrier frequency will be transmitted over the outgoing line.

What I claim is:—

1. In a signaling system for transmitting signals of interrupted carrier current over a line, a gas discharge tube for limiting the input from said line, simple resonant circuits included in said line ahead of said discharge tube, a thermionic relay having a responding relay in its 100 anode circuit, and circuits including a resistance, a tuned circuit, and a rectifier for feeding the limited input controlled by said discharge tube to said thermionic valve.

2. In a signaling system for transmitting signals of interrupted carrier current over a line, a limiting device included in the receiving end of said line, tuned circuits included in said line ahead of said limiting device, a relay, and a simple filter circuit interposed between said limiting device and said relay for controlling the operation of said relay only in response to signals of said carrier frequency of the proper magnitude.

3. In a signaling system for transmitting signals of interrupted carrier frequency having a 110 narrow side band, a thermionic valve, a limiting device for controlling the output of said valve, said limiting device having a tendency to lengthen the signal impulses, and means including circuits for modifying the amplification characteristic of said valve by increasing the negative grid voltage in response to the receipt of signals of large voltage amplitude thereby shortening the signal impulses received in order to compensate for the action of said limiting device.

4. In a signaling system for transmitting signals of interrupted carrier frequency having a narrow side band, a thermionic valve, a limiting device for controlling the output of said valve, said limiting device having a tendency to change 120 the length of the signal impulses received, and means including circuits for altering the grid bias of said valve in response to the receipt of signals of large voltage amplitude thereby altering the signal impulses received in order to compensate for the action of said limiting device.

5. In a signaling system for transmitting signals of interrupted carrier current over a line, a thermionic valve having a grid and an anode circuit at the receiving end of said line, a resistance and a condenser combination, the input at the receiving end of said line being fed to the grid of said valve by way of said resistance and condenser combination, a rectifier for rectifying the output of said valve, said condenser 140

being charged by said rectified current in response to the receipt of current of large voltage amplitude, said condenser discharging during the time current of small voltage amplitude is received between successive signal pulses for increasing the negative grid bias on said valve, said increased negative grid bias thereby reducing the effect or entirely preventing the passage of signals of small magnitude between signals of large magnitude.

6. In a signaling system, a first alternating current source of a particular frequency, a thermionic valve, a second alternating current source of a different frequency, a signaling line, a tuned circuit for said second frequency including a transformer and a condenser connected to said signaling line, said transformer coupling said tuned circuit with the anode circuit of said valve, said tuned circuit having a high impedance to currents of frequencies other than said second frequency, means for transmitting a signal of the first frequency to said valve, the anode current of said valve increasing responsive thereto for reducing the anode-cathode impedance of said valve, and a second transformer included in the anode circuit of said valve and connected to said second source for impressing a signal of the second frequency on said signaling line in response to said reduced impedance.

7. In a signaling system for transmitting signals of interrupted carrier current of a particular frequency over a line, the transmitting circuits of said line including resonant circuits tuned to two frequencies respectively slightly above and slightly below said carrier frequency, the receiving circuits of said line including resonant circuits tuned to two different frequencies also respectively slightly above and below said carrier frequency, and means including said circuits in tandem for producing substantially flat response curves over the range representing the width of the side bands employed in response to the transmission of signals of said particular frequency over said line.

8. In a signaling system as claimed in claim 7 wherein the two tuned resonant circuits in the transmitting and receiving circuits consist substantially wholly of capacity and inductance, and in which the second of each of the two tuned circuits includes only a small tapping of the inductance of its associated first circuit.

9. In a signaling system as claimed in claim 7 including a low resistance connected in series with the inductance and capacity of the second tuned circuit in the receiving circuit for controlling the output from said line.

10. In a signaling system for transmitting signals of interrupted carrier current over a line, a gas discharge tube for limiting the input from said line, simple resonant circuits included in

said line ahead of said discharge tube, a thermionic valve having a responding relay in its anode circuit, circuits including a resistance, a tuned circuit, and a rectifier for feeding the limited input controlled by said discharge tube to said valve, said valve having a normally high grid bias for restricting the flow of anode current through said relay until the limited input current reaches a predetermined point.

11. In a signaling system for transmitting signals of interrupted carrier current over a line, a gas discharge tube for limiting the input from said line, a thermionic valve having a responding relay in its anode circuit, a tuned circuit for feeding the limited input controlled by said discharge tube to the grid circuit of said valve, a rectifier, a condenser and a resistance in said grid circuit, the input from said tuned circuit being applied through said rectifier to said condenser and resistance in parallel to the grid of said valve, said valve having a normally high grid bias for restricting the flow of anode current through said relay until the said input current reaches a predetermined value, and a further resistance connecting the grid of said valve to said rectifier for maintaining the voltage across said condenser above the flow of normal grid current during signal transmission.

12. In a signaling system as claimed in claim 1 including a resistance in said tuned circuit, the value of said resistance in the tuned circuit determining the length of the signal flow in the relay anode circuit of said valve.

13. In a signaling system for transmitting signals of interrupted carrier frequency having a narrow side band, a thermionic valve, a limiting device for controlling the output of said valve, said limiting device having a tendency to change the length of the signal impulses received, and circuits including a resistance in the cathode-anode circuit of said valve, a rectifier, a condenser and a resistance in parallel in the grid circuit of said valve for altering the grid bias of said valve in response to the receipt of signals of large voltage amplitude thereby altering the signal impulses received in order to compensate for the action of said limiting device.

14. In a signaling system for transmitting signals of interrupted carrier current over a line, a neon tube for limiting the input from said line, simple resonant circuits included in said line ahead of said neon tube, a first thermionic valve, a second thermionic valve, a transformer having three windings, the first of said windings connected to said neon tube, the second of said windings included in the anode circuit of said first valve, and the third winding for feeding the signaling currents to said second valve.
